UNITED STATES PATENT OFFICE.

WILLIAM HENRY CLAY BRENNER, OF POUGHKEEPSIE, NEW YORK.

CONTROLLING DEVICE FOR ELEVATOR-BRAKES.

No. 916,835.

Specification of Letters Patent.

Patented March 30, 1909.

Application filed November 17, 1908. Serial No. 463,086.

To all whom it may concern:

Be it known that I, WILLIAM HENRY CLAY BRENNER, a citizen of the United States, and a resident of Poughkeepsie, in the county of 5 Dutchess and State of New York, have invented a new and Improved Controlling Device for Elevator-Brakes, of which the following is a full, clear, and exact description.

The purpose of this invention is to provide 10 novel details of construction for a brake rope controller, whereby the rope will be pulled upon by the upward travel of the elevator platform, and automatically stop said platform at a desired point, that will 15 render the platform level with a floor of the building in which the elevator is installed.

The invention consists in the novel construction and combination of parts, as is 20 hereinafter described and defined in the appended claims.

Reference is to be had to the accompanying drawings forming a part of this specification, in which similar characters of reference indicate corresponding parts in all the 25 views.

Figure 1 is a sectional side elevation of a floor of a building at a well hole therein, a like view of an elevator device, and a side view of the improvement mounted on the 30 floor of the building and on the platform of the elevator; Fig. 2 is a vertical transverse sectional view, substantially on the line 2—2 in Fig. 3; Fig. 3 is an enlarged front elevation of the improvement seen in the direction of the arrow α in Fig. 1; and Fig. 4 is a transverse sectional view substantially on the line 4—4 in Fig. 3.

Briefly stated, this invention relates to a 40 class of elevators generally used for the transportation of material from one floor in a building to another, the means for stopping and starting the elevator platform being controlled by a brake rope, that is pendent in or near the well holes in the floors 45 through which the elevator moves.

In the drawings, that show the construction and application of the improvement, A indicates one floor of a plurality in a building and A', the side timbers that define the 50 opening or well hole frame A² through which the elevator platform travels. The platform B, of any approved construction, is reciprocal in the well hole mentioned, and is in this construction thereof represented 55 as pendent from a rope C, that is shown broken, but in completed condition engages

apparatus not shown, which moves the rope upwardly and correspondingly actuates the platform. A portion of a brake rope 5, that is normally hung pendent in the well hole 60 near one defining timber A' thereof, is shown, this rope in condition for service being endless and connected at its upper bight with the controlling means employed to stop and start the elevator platform; this 65 being common to this class of elevators is omitted from the drawings.

It is the purpose of this invention, as before mentioned, to provide simple, novel means for automatically arresting the platform of the elevator when it is level with a floor in the building, which is in this case, effected by an upward movement of the 70 brake rope 5, that is adapted by a downward movement thereof, for releasing the 75 brake and permitting the free travel of the elevator.

The improvement is extremely simple and practical, consisting of the following described parts and their combination. 80

Two similar bracket arms 6, each provided with a foot flange 6^a, that projects laterally therefrom, are secured by means of said flanges upon a timber A', that is adjacent to the pendent brake rope 5. The elongated plate-like bracket arms 6, are spaced apart a proper distance in a vertical plane, and between each pair of oppositely positioned ends of said bracket arms, hubs a are formed, that in pairs support a pintle shaft 90 b, whereon a preferably grooved pulley c is rotatably mounted, thus disposing the similar pulleys c rotatably at respective ends of the arms. Upon the adjacent upright walls of the bracket arms 6, 6, a pair of similarly 95 shaped slideways 7, 7, are formed or secured, which are preferably sloped on their sides toward the adjacent edges d thereof, as is clearly shown in Fig. 4, and these edges are spaced apart sufficiently to permit the 100 free passage of the brake rope between them. Upon one run of the brake rope 5, an enlargement 8, preferably in the form of a ball, is secured. The rope 5 is so relatively arranged that one run thereof will occupy 105 a vertical plane, coincident with that occupied by the grooved peripheries of the pulleys c, and the channel between the slide-ways 7.

The normal position of the ball 8 is 110 shown in Figs. 1 and 2, which disposes the run of the brake rope 5 adjacent to the side

of the elevator platform B, that is nearest to the bracket arms 6 when said platform is elevated. Upon the side of the platform that the pendent brake rope 5 nearly has 5 contact with, an abutment arm 9 is secured, that projects outward beyond the platform. The arm 9 is substantially V-shaped, but is convexed on the lower side thereof, and in the angular outer end a notch e is formed 10 that receives the brake rope 5.

It will be seen in Figs. 1 and 2, that the run of the brake rope 5 having the fixed ball 8 thereon, engages the upper pulley e upon its periphery at a point farthest from 15 the vertical plane traversed by the abutment arm 9, and that the brake rope 5, below said ball, has contact with the lower grooved pulley e at a point in vertical alinement with the forked end of the abutment arm.

Assuming that the brake rope 5 has been 20 manually adjusted by a downward pull, so that the ball 8 occupies the space below the slideways 7 on the bracket arms 6, and that the elevator platform B is thus caused, by 25 its actuating mechanism, to travel upward, the abutment arm 9 will slide upon the brake rope 5, pass over the lower grooved pulley e and impinge upon the lower side of the ball 8. The contact of the arm 9 with 30 the ball 8 will pull upward upon the rope 5, and this will continue while the ball slides upon the ways 7. The relative arrangement of the parts is such that when the upper surface of the platform B becomes 35 level with the like surface of the floor A, the ball 8 will pass into the space between the bracket arms 6, above the slideways 7, which will adapt the ball to slide down on the opposite sides of the slideways 7, when 40 the draft rope is pulled upon to start the elevator platform, the ball then assuming its normal position in the lower opening between the bracket arms 6, as shown in Figs. 1 and 2.

It will be seen that by the construction 45 and arrangement of the improved controlling device, the platform of an elevator of the character described, will be automatically arrested at each one of a tier of floors 50 in a building provided each is supplied with the controlling device, and will remain stationary until the brake rope is pulled down,

which will release the brake and also restore the controlling device to its normal position for service when the elevator is again started upward. 55

Having thus described my invention, I claim as new and desire to secure by Letters Patent:

1. A controlling device for an elevator, 60 comprising in combination with the elevator-car and the brake rope for controlling the same, spaced slideways between which the rope passes, an enlargement on the rope, and a projection on the elevator-car for engaging 65 the enlargement, said enlargement being of greater diameter than the space between the slideways for the purpose set forth.

2. A controlling device comprising in combination with the elevator-car, two 70 spaced vertical slideways fixed at the point where the elevator is to be controlled, a brake rope pendent and passing between said slideways, a ball fixed on the brake rope, that will slide on the slideways when 75 the rope and ball are moved upward for stopping the platform, and an abutment arm projected from the elevator-car in the path of the ball for contact therewith when the elevator moves upward. 80

3. The combination with a well hole frame in a building, and an elevator platform reciprocal through said well hole frame, of a brake-controlling device for the platform, embodying two spaced bracket arms secured 85 on a member of the well hole frame, a slide-way on each bracket arm, a pendent brake rope passing between the slideways, pulleys on the ends of the bracket arms engaged by the rope, a ball fixed on the rope which 90 slides on the slideways when moved upward, and an abutment arm on the platform having a notched projecting end that receives the brake rope and is adapted to impinge upon the ball when the platform moves upward. 95

In testimony whereof I have signed my name to this specification in the presence of two subscribing witnesses.

WILLIAM HENRY CLAY BRENNER.
